UNITED STATES PATENT OFFICE.

HUGO GÜNTHER, OF CHEMNITZ, SAXONY, GERMANY, ASSIGNOR OF ONE-HALF TO MATTHÉE HERFURTH, OF SAME PLACE.

KNITTING-MACHINE.

SPECIFICATION forming part of Letters Patent No. 253,922, dated February 21, 1882.

Application filed November 20, 1880. (No model.)

To all whom it may concern:

Be it known that I, HUGO GÜNTHER, of Chemnitz, in the kingdom of Saxony, in the Empire of Germany, have invented a new and Improved Knitting-Machine, (for which neither I nor any one with my consent or to my knowledge has any foreign patent,) of which invention the following is a specification.

Figure 1 is a front view of part of a knitting-machine, showing my improvement. Fig. 2 is a similar view, showing the parts in a different position. Fig. 3 is a front view of a modification thereof; Fig. 4, a top view of the said modification; and Fig. 5, a cross-section on the line 15 *c c*, Fig. 4.

The object of this invention is to provide a knitting-machine—such, for example, as the Lamb knitting-machine—with an adjustable needle-plate, and with mechanism for moving said needle-plate, so that at any one time the operator can shift the needle-plate, and with it the position of each needle, thereby producing certain changes in the design of the work produced, which without such shifting could 25 not be brought about.

My invention consists in combining with the movable needle-plate certain locking devices and certain unlocking devices which are operated at will, all as hereinafter more fully described.

In the accompanying drawings, the letter A represents the reciprocating carriage of a Lamb knitting-machine. This carriage is moved back and forth in the usual manner by the means 35 of a crank. B is one of the needle-plates, grooved to receive the latched needles. This needle-plate is placed upon the supporting-frame C, and capable of lateral movement between two posts or blocks, *a* and *b*, that form a 40 part of the supporting-frame C. In Fig. 1 the needle-plate is shown as moved against the post *a*, and in Fig. 2 as moved against the post *b*. In either position the plate B is locked by one of a pair of spring-latches, D and E, whose 45 projecting noses are by suitable springs, *d*, forced into the space between the needle-plate and the post from which the needle-plate has been withdrawn. Thus in Fig. 1 the latch E,

in Fig. 2 the latch D, locks the needle-plate in its position.

From the ends of the needle-plate project rods F and G, having projecting lugs at their outer ends, and between these lugs and the corresponding posts of the supporting-frame enters the upwardly-extending member of an 55 elbow-lever, H, there being two such elbow-levers, one pivoted to each post, as shown. The carriage A receives in suitable apertures projecting pins *g* and *h*, and whenever it is desired to shift the needle-plate the carriage is 60 moved so far that one of the pins—say the pin *g*, as in Fig. 1—reaches a projecting incline, *i*, of the nearest latch, D, and presses this latch down, as in Fig. 1, and after that, the movement of the carriage being continued in the 65 direction of the arrow shown in Fig. 1, the pin *g* strikes the outer arm of the lever H, and thereby causes said elbow-lever, by drawing on the pin F, to pull the needle-plate toward the post *a*, thus bringing it into the position 70 shown in Fig. 1. Having been drawn toward the post *a*, the needle-plate holds the latch D down, but liberates the latch E, which now 75 springs up, and locks the needle-plate by entering between the post *b* and the said needle-plate. The knitting can now proceed as long as desired with this position of the needle-plate.

It is well known that the full stroke of the carriage A is not required in all species of knitting; and whenever the needle-plate is to be shifted again the carriage is moved so as to cause the pin *h* to actuate the latch E, and to draw the plate B back to the post *b*.

The modification which is shown in Figs. 3, 85 4, and 5 consists in substituting for the devices which move and lock the needle-plate, and that are shown in Figs. 1 and 2, analogous but slightly different elements of a corresponding combination. According to this modification I connect with the back of the needle-plate a vibrating lever, L, which is pivoted to a stationary support, and receives below said pivot, in a slot, a pin that projects from the needle-plate. The upper part of the lever L 90 connects with a slide, M. This slide has pro-

jecting ends *l* and *m*, which can be struck by the pins *g* and *h* of the carriage A, and which, when struck, will cause the slide M to move in the direction of the carriage, and the lever L to be vibrated, and the needle-plate to be moved in the direction opposite to that in which the carriage is moved.

The locking is performed by means of spring-catches *p*, that fall into notches that are cut into the needle-plate. These spring-catches are lifted at the proper time by inclined portions *s* of the slide M, so as to allow the needle-plate to move. Thus in the position shown in Fig. 3 a projecting pin, *h*, of the carriage has struck the end *m* of the slide M, and has thereby pushed the inclined portion *s* from under the nearest catch *p*, lifting that out of the notch of the plate B, and permitting, as the motion of the slide M is continued, the movement of the plate B in the desired direction. The upper end of the lever L plays in a slot of the slide, so as to permit this slide to first lift the catch before the plate B will be actually moved. The other catch *p* drops into its notch

the moment the needle-plate has been moved 25 to the end of its stroke.

I claim—

1. In a knitting-machine, the combination of a reciprocating carriage, A, having projecting pins *g* and *h*, with the needle-plate B, devices for moving the same, and with two locking-catches, all arranged so that the needle-plate will always be locked by one of the catches, as set forth, and in position to be moved by one of the projecting pins of the carriage, substantially as specified.

2. The combination of the carriage A, having pins *g* and *h*, with needle-plate B, having pins F and G, and with the levers H and spring-catches D and E, all arranged to operate substantially as described.

The above description of my invention signed by me this 21st day of September, A. D. 1880.

HUGO GÜNTHER.
